UNITED STATES PATENT OFFICE.

CHARLES E. HEYER, OF CHICAGO, ILLINOIS, ASSIGNOR TO THE BARNHART BROTHERS & SPINDLER, OF SAME PLACE.

DESIGN FOR A FONT OF PRINTING-TYPE.

SPECIFICATION forming part of Design No. 25,552, dated May 26, 1896.

Application filed April 13, 1896. Serial No. 587,414. Term of patent 7 years.

To all whom it may concern:

Be it known that I, CHARLES E. HEYER, a citizen of the United States, residing at Chicago, county of Cook, and State of Illinois, have invented and produced a new and original Design for a Font of Type, which is fully set forth in the following specification, reference being had to the accompanying drawing, forming a part thereof.

This design comprises lower-case letters, capitals, Arabic numerals, character &, dollar-mark, and points. It is very condensed in respect to the "counters," but expanded in respect to the stems and body-lines, which are very heavy, the general effect to the eye being that of an intensely-opaque condensed body. Serifs on all stems are of wide angle, and in comparison with the heavy body-lines appear to be rudimentary and having the effect on the heavy stems of merely sharpening the angle and rendering the line more brilliant, while on light stems, as last stroke of lower-case v and w, the serif is prominent, although, in fact, not more pronounced than on the heavier stems. The completely-in- closed counters of the oval element of lower-case g, lower-case o, capital O, and capital Q are a bold circumflex swell, having the appearance of being set obliquely to the axis of the oval, though the terminal points are in fact symmetrically situated with reference to the axis. Open oval elements generally termi-

nate expanded and transversely concaved, as the upper terminal of lower-case a, both terminals of lower-case c e s, capital C, upper terminal of capital G, both terminals of capital S, upper terminal of character & and of interrogation-point, both terminals of dollar-mark, figure 2, both terminals of figure 3, lower terminal of figure 5, upper terminal of figure 6, and lower terminal of figure 9. Similarly formed are the upper terminal of lower-case f, upper characteristic of lower-case g, hook of lower-case j, and characteristic of capital Q. The characteristic hook of lower-case j is produced by apparently recessing the side of the stem, the hook, in fact, scarcely extending beyond the left-hand line of the stem. The stems of lower-case a and t are deflected to the right at the line and terminated obliquely to the line, leaving an angle projecting below the line. The characteristic cross-stroke of capital A is a very short circumflex swell, set exceptionally low. The characteristic cross-stroke of capital H is doubled, the upper line being exceptionally high.

I claim—

The design for a font of type herein shown and described.

CHAS. E. HEYER.
